Patented Jan. 3, 1911.

UNITED STATES PATENT OFFICE.

BYRDE B. HEFFELFINGER, OF SYRACUSE, INDIANA.

SCRUBBING-MACHINE.

980,779.

Specification of Letters Patent. Patented Jan. 3, 1911.

Application filed September 10, 1909. Serial No. 517,092.

To all whom it may concern:

Be it known that I, BYRDE B. HEFFELFINGER, a citizen of the United States, residing at Syracuse, in the county of Kosciusko and 5 State of Indiana, have invented a new and useful Scrubbing-Machine, of which the following is a specification:

This machine relates to machines for scrubbing floors, etc., and its object is to provide 10 a machine of this character which can be readily manipulated and which is provided with novel means for thoroughly scrubbing the surface on which the machine is mounted and for taking up the dirty water upon said surface and discharging it into a receptacle carried by the said machine.

Another object is to provide means for supplying water to the scrubbing brushes, 15 said means being constantly under the control of the operator.

Another object is to provide means for holding the scrubbing brushes yieldingly in contact with the surface to be cleaned for the purpose of automatically taking up wear, 20 upon the brushes and for causing them to follow the contour of any uneven surfaces being cleaned.

With these and other objects in view the invention consists of certain novel details of 25 construction and combinations of parts hereinafter more fully described and pointed out in the claim.

In the accompanying drawings the preferred form of the invention has been 30 shown.

In said drawings:—Figure 1 is a central vertical longitudinal section through the machine, a portion of the body of said machine being shown in side elevation. Fig. 2 35 is a section on line A—B Fig. 1. Fig. 3 is a section on line C—D Fig. 1. Fig. 4 is an enlarged detail view of a portion of the mopping belt. Fig. 5 is a plan view of a portion of the inner face of the belt and showing 40 the band used in connection therewith. Fig. 6 is a detail view of portions of the two wringing rolls and the spring connection 45 therebetween.

Referring to the figures by characters of 50 reference 1 designates a housing open at the bottom and provided adjacent the front thereof with studs 2 on which are journaled the front supporting wheels 3 of the machine. Each of these wheels has a beveled 55 gear 4 secured to its inner face, it being understood that the wheels are housed within

the machine as clearly indicated in Fig. 2. Each beveled gear 4 meshes with the beveled gear 5 feathered upon a spindle 6 which is revolvably and slidably mounted within a 60 cross-bar 7 connecting the sides of the housing near the front thereof, said spindle also extending through the top of the housing. A brush 8 is secured to the lower end of spindle 6 and interposed between this brush 65 and the gear 5 is a spring 9 which serves to hold the brush normally pressed downwardly against the surface thereunder. Downward movement of the gear 5 is of course prevented by the gear 4 meshing 70 therewith, and the bar 7 prevents upward displacement of the gear 5. Two brushes 8 are of course utilized, said brushes being arranged side by side and each brush being actuated by one of the wheels 3 and the 75 mechanism connected thereto.

Arranged transversely within the housing 1 and immediately in rear of the brushes 8 is a receptacle 10, the top of which is open and inclined and journaled within the housing and directly above this receptacle are wringer rollers 11 and 12 bearing within the end portions of spring arms 13 extending from a coil 14 which is secured in any suitable manner to a stud 15 extending inwardly 80 from the housing. The spring arms 13 serve to hold the rolls 11 and 12 normally pressed together. Mounted on the upper roll 11 is an endless wiping belt 16 formed of canvas or other strong fabric, on the 85 outer or working face of which are secured particles of sponge, as indicated at 17. It is to be understood that these particles can be attached in any preferred manner and may be interwoven with the fabric. Also 90 instead of utilizing sponge particles pieces of any other suitable absorbent material may be employed. Secured upon the inner surface of the belt 16 and along the longitudinal center thereof is a metal band 18 having 100 apertures 19 therein at regular intervals, said band being designed to extend around a sprocket 20 the teeth of which work within the apertures 19. This sprocket is located at the center of a roll 21 mounted on a shaft 105 22 which is journaled in the side of housing 1 near the rear thereof, there being a gear 23 upon the shaft and at one side of the housing, said gear meshing with a smaller gear 24. This last mentioned gear is secured to a shaft 25 on which is mounted a rear supporting roller 26. An idler roller

27 is journaled within the housing and serves to hold a portion of the lower ply of belt 16 below the bottom of the housing. This downwardly projecting portion of the 5 belt is in substantially horizontal alignment with the bottom of each brush 8.

A yoke 28 embraces and is pivotally connected to the housing and has a handle 29 extending from the center thereof. Se- 10 cured to this handle is a tank 30 to the out- let 31 of which are connected flexible tubes 32 designed to convey liquid from the tank to soap-holders 33 arranged in the front portion of the housing 1, one holder being lo- 15 cated close to each of the brushes 8, so that the liquid upon leaving the boxes or holders will flow downwardly on to the brushes. A valve 34 is arranged within the outlet 31 and may be actuated by means of a lever 35 20 fulcrumed on yoke 28 and connected to an operating lever 36 by means of a rod 37. This operating lever 36 is located close to the grip 38 of the handle so that it can be conveniently reached by a hand grasping the 25 grip.

When it is desired to use the machine the boxes or holders 33 are filled with soap or other suitable cleansing composition and the tank 30 is filled with water. When the ma- 30 chine is pushed over the surface to be cleaned the wheels 3 transmit motion to the respective brushes through the gears 4 and 5 and these brushes will be rotated in opposite directions simultaneously and the springs 9 35 will press them yieldingly upon the surface being cleaned. While these brushes are rotating the operator can open the valve 34 so as to permit water to flow into the boxes or holders 33 and thence on to the brushes. 40 As the machine passes over the surface to

be cleaned the wiping belt 16 will be actuated by the rear wheels 26 which transmit motion thereto through the gears 24 and 23 and the sprocket 20. This wiping belt will move in the direction indicated by the arrow 45 in Fig. 1 and the absorbent particles 17 thereon will collect the moisture from the surface and convey it upwardly between the rolls 11 and 12 which squeeze it therefrom and cause it to flow into the receptacle 10. 50

It will be seen that the machine can be very readily manipulated and will operate to efficiently scrub any surface over which it may be pushed.

Various changes may of course be made 55 in the construction and arrangement of the parts without departing from the spirit or sacrificing the advantages of the invention.

What is claimed is:

A scrubbing machine comprising a wheel- 60 supported housing, grooved rolls mounted within and extending transversely of the housing, a band seated within the grooves and having apertures, a sprocket engaging the apertured band, a tank within the hous- 65 ing, an absorbent belt connected to the band and mounted on the grooved rolls, a spring pressed roll co-operating with one of the rolls at a point above the tank for wringing moisture from the belt, and scrubbing 70 brushes mounted within the housing and actuated by a supporting wheel.

In testimony that I claim the foregoing as my own, I have hereto affixed my signature in the presence of two witnesses.

BYRDE B. HEFFELFINGER.
